EARL F. DUNN, OF MAMMOTH, AND ENOCH MUHLESTEIN, OF SILVER CITY, UTAH.

PURSE.

Application filed February 23, 1927. Serial No. 170,366.

The present invention is directed to improvements in purses.

- The primary object of the invention is to provide an article of this character which is formed wholly from suitable leather, the construction being such that the use of metallic frames and fasteners are eliminated in order that the purse can not be injured by breakage or cause wear upon the clothes of the user.
- 10 Another object of the invention is to provide a purse so constructed that it can be conveniently opened or unfolded to permit convenient access to the contents and when folded or closed, will be held against accidental opening.

In the accompanying drawing:

Figure 1 is a perspective view of the purse showing the same in its open position.

Figure 2 is a longitudinal sectional view 20 showing the purse in its open or unfolded position.

Figure 3 is a transverse sectional view through the purse when folded.

The purse comprises a tray section 1 having 25 a wall 2 which extends around the sides and ends of said tray, said wall having its edge turned inwardly and stitched, as at 3, to provide a continuous bead 4, the purpose of which will appear later.

30 Formed integral with the bottom of the tray and hingedly connected thereto by the flexible joint 5 is a section 6 having its side wall stitched, as at 7, to the side wall 8 of the section 9, the respective side walls being 35 turned inwardly, as at 10. A partition 11 is provided and occupies a position between the sections 6 and 9 and has its side edges stitched to the inturned edges of the respective sections. In this manner compartments 12 and 40 13 are provided, said partition having its for-

ward edge provided with an integral flap 14, and serves to normally close the open end of the compartment 13.

By turning the respective edges of the sections 6 and 9 inwardly, a groove 15 is formed 45 so that when the sections are folded within the confines of the tray 1 the bead 4 carried by the wall of said tray will enter said groove and thus retain the sections and tray against accidental opening. A tab 16 is secured between the sections 6 and 9 at the rear thereof and serves as a finger hold to permit the sections to be readily unfolded.

50 The compartment 12 is so arranged that when the purse is opened coins in said compartment pass therefrom and will slide upon the tray, while the compartment 13 is preferably designed for containing paper currency, it will be of course understood that coins may be placed therein if desired.

55 The entire purse is formed from suitable leather and may be ornamented or finished in any manner desired.

Having thus described the invention, we claim:

60 A purse comprising a tray including a side wall, said side wall having its ends formed with a continuous bead, a section flexibly connected to the tray, a second section, the sections defining compartments, said sections 65 having walls formed with inturned edges capable of being stitched to each other to provide a groove between the sections capable of engaging said bead when the sections are confined within the wall of the tray.

70 75 In testimony whereof we affix our signatures.
